UNITED STATES PATENT OFFICE.

ALLEN S. NERO, OF BOTTINEAU, NORTH DAKOTA.

OPERATING MECHANISM FOR WASHING-MACHINES.

1,178,593.

Specification of Letters Patent. Patented Apr. 11, 1916.

Application filed March 29, 1915. Serial No. 17,855.

To all whom it may concern:

Be it known that I, ALLEN S. NERO, a citizen of the United States, residing at Bottineau, in the county of Bottineau and State 5 of North Dakota, have invented certain new and useful Improvements in Operating Mechanism for Washing-Machines, of which the following is a specification, reference being had to the accompanying drawings.

10 My present invention relates broadly to new and useful improvements in washing machines and similar articles and has particular reference to that class known as pounder machines.

15 In my Patent Number 934,458, I have disclosed a machine of the above character in which the plunger operating mechanism is so constructed that upon each reciprocation of the plungers, they will turn through a 20 small arc so that they are, during the use of the machine, continuously presented to the clothes lying in different parts of the tub.

25 The principal object of my present invention is to provide an improved operating mechanism for the plunger which will efficiently accomplish this desired object of turning the plungers through a small arc upon each reciprocation of the plunger rod.

30 The above, and other incidental objects of a similar nature, which will be hereinafter more specifically treated are accomplished by such means as are illustrated in the accompanying drawings, described in the following specification, and then more particularly pointed out in the claims which are appended hereto and form part of this application.

With reference to the drawings, wherein there has been illustrated the preferred embodiment of this invention, as it is reduced to practice, and throughout the several views of which similar reference numerals designate corresponding parts, Figure 1 is a front elevation; Fig. 2 is a top plan view; Fig. 3 is a vertical section, showing the plunger in elevated position; and Fig. 4 is a vertical section showing the plunger in lowered position.

As best disclosed as an operative entirety 50 in Fig. 1 of the accompanying drawings, my improved machine includes a plurality of funnel-shaped plungers 10 which are yieldably attached to and carried by a body bar 11. These plungers are, of course, mounted 55 for reciprocation within the tub (not shown) and are actuated by means of a plunger rod

12 and an operating mechanism which is mounted upon the cover 13 of the tub. The operating mechanism includes a substantially U-shaped frame, the bight bar 14 of which constitutes an attaching plate 15, through which bolts 16 are passed to secure the bar to the member 13. The vertical arm 17 of this U-shaped frame is provided at its upper end with a bearing 18, in which the 60 crankshaft 19 is terminally journaled. The other end of this crankshaft is journaled in a bearing 20 formed on the upper end of a vertical bracket arm 21 which is provided with a lateral foot 22 adapted to be received 65 between a pair of upstanding lugs 23 formed on the bar 14 and to be held in position thereon by a bolt or similar fastening device 24. Collars 25 and 26, provided with set screws 27 are applied to the main shaft 70 and disposed against the opposite ends of the bearings 18 for holding the shaft against longitudinal movement therethrough. The outer end of the main shaft is preferably 75 equipped with a crank wheel 28, although a 80 crank or similar device may be employed, if desired.

Adjacent to one terminal, the body bar 14 is provided with a guide sleeve 29 through which freely extends the plunger rod 12. 85 The upper end of the plunger rod carries a sleeve 30 in which it is rotatable and from which it is held against withdrawal by means of a cap 31. This cap 31 is, as shown in Figs. 3 and 4 threaded upon the upper 90 terminal of the plunger rod. The lower end of the sleeve 30 bears upon the annular shoulder 32 which is formed at the junction of the enlarged and reduced portions of the plunger rod. A vertically extending guide 95 rib 33 is formed exteriorly on the sleeve 30 and is seated for vertical reciprocation through the slot or groove 34 formed in the terminal of the horizontal arm 35. The arm 35 extends at right angles to the arm 36 of 100 the U-shaped frame, as best shown in Fig. 1. It will now be seen that the sleeve 30 is adapted to reciprocate with the plunger rod and that the rod is rotatable therein, the sleeve being held against rotation by the 105 rib 33.

In operatively connecting the crank shaft and the sleeve 30 so that the rotation of the shaft will cause the reciprocation of this member and consequently of the plunger 110 rod, I employ a cross head 37 and a crank 38. The cross head 37 is formed integrally

with the sleeve and extends in a horizontal plane. The cross head is provided with a longitudinally extending slot in which is disposed the roller 39 carried on the terminal stub 40 of the crank. Upon reference to Figs. 1 and 2, it will be seen that the rotation of the main shaft will, through the medium of the crank, cause the vertical reciprocation of the cross head and consequently of the plunger rod.

Mounted upon the plunger rod immediately below the sleeve 30, is a ratchet wheel 41, the integrally formed collar 42 of which is keyed to the plunger rod by means of a set screw 43. It will now be seen that if the ratchet wheel is given a partial turn, during each reciprocation of the plunger rod, that the plungers 10 will be constantly turned so as to be engaged against all the clothes lying in the tub at different portions thereof. As a means for giving this desired partial turn to the ratchet wheel, once during each reciprocation of the plunger rod, I employ a substantially L-shaped pawl which is formed from a single length of wire bent to produce a pair of rectangularly related arms 44 and 45 and an eyelet 46 which is formed at the junction of these arms. This eyelet 46 receives the pivot bolt 47 which passes through a horizontally disposed bracket arm 48 formed integrally with the arm 21. The terminals of the arms 44 and 45 are bent at right angles so that they project over the periphery of the ratchet wheel. The stub 49 of the arm 44 is disposed above the ratchet wheel, while the stub 50 of the arm 45 is disposed below the ratchet wheel.

Relative to the operation of the double arm pawl, it is to be noted that when the ratchet wheel is in lowermost position, at the termination of the downward movement of the plunger rod, it has engaged the stub 50, swinging the arm 45 to vertical position and the arm 44 to horizontal position. Upon the return upward movement of the plunger rod, the ratchet wheel engages the stub 49 and swings the arm 44 on up above a horizontal position. This upward swinging movement of the arm 44, of course, causes the movement of the stub toward the vertical plane of the U-shaped frame. Thus the ratchet wheel is given a partial turn and the plungers are consequently also partially rotated. Stop shoulders indicated at 51 and 52 are provided to limit the swinging movement of the arms 44 and 45 beyond an arc of 90°.

From the foregoing description it will now be observed that I have designed a relatively simple and, at the same time, efficiently operated mechanism which serves to simultaneously reciprocate and turn the plungers in the machine. I desire to now emphasize the fact that the ratchet wheel constitutes not only the means which is actu-

ated by the pawl for turning the plunger, but that it also constitutes the means for returning the pawl to its initial position upon the downward movement of the plunger.

In reduction to practice, it has been found that the form of this invention illustrated in the drawings, and referred to in the above description as the preferred embodiment is the most efficient and practical; yet realizing that the conditions concurrent with the adoption of this device will necessarily vary, it is desirable to emphasize the fact that various minor changes in the details of construction, proportion and arrangement of parts may be resorted to, when required, without sacrificing any of the advantages of this invention, as defined by the appended claims.

What is claimed is:

1. In an actuating mechanism for vertically reciprocable plunger rods, means for reciprocating the plunger rod, a ratchet wheel keyed on the plunger rod, and a double arm pawl having one arm engageable with the upper face of the ratchet wheel and the other arm engageable with the lower face of the ratchet wheel, said pawl being operable for turning the wheel once during each reciprocation of the plunger rod.

2. In an actuating mechanism for vertically reciprocable plunger rods, means for reciprocating the plunger rod, a ratchet wheel keyed on the plunger rod, and a double arm pawl engageable with the ratchet wheel for turning the plunger rod in an arc, during each upstroke thereof, the arms of said pawl being disposed at right angles to each other and being located one above and one below the ratchet wheel, said ratchet wheel being adapted to engage one arm during the down stroke of the rod for setting the other arm and being adapted to engage said last mentioned arm upon the upstroke of the plunger rod and to be turned thereby.

3. The combination with a reciprocatable plunger rod, of means for intermittently rotating the rod, said means including a ratchet wheel fixed upon the rod and a pawl mounted upon a fixed pivot for oscillation in a plane parallel to the direction of reciprocation of the rod, the pawl having a body portion extending in a plane parallel to the plane of reciprocation of the ratchet wheel and having a terminal end extending over the face of the ratchet wheel, and means for limiting the movement of the pawl in one direction to thereby permit the ratchet wheel to move out of engagement with the pawl upon a stroke in one direction and into engagement with the pawl upon a stroke in the other direction.

4. In an actuating mechanism for vertically reciprocable plunger rods, means for reciprocating the plunger rod, and means for periodically turning the rod, said means

including a ratchet wheel fixed upon the rod, and a double arm pawl mounted for oscillation and having a relatively stationary pivot, one arm of said pawl being periodically engageable with the ratchet wheel for turning the same, the other arm of said pawl being actuated upon the downward movement of the plunger rod to swing the first mentioned arm into operative position for engagement with the ratchet wheel, upon the upward movement of the rod.

5. In an actuating mechanism for vertically reciprocable plunger rods, means for reciprocating the plunger rod, and means

for periodically turning the rod, said means including a ratchet wheel fixed upon the rod, a double arm pawl mounted for oscillation in a vertical plane upon a relatively stationary pivot, the arms of said pawl being angularly related and being alternately engageable with the ratchet wheel during the reciprocation of the same.

10 In testimony whereof I hereunto affix my signature in the presence of two witnesses.

ALLEN S. NERO.
